UNITED STATES PATENT OFFICE.

WILLY MEYER, OF HAMELN, GERMANY.

SEED-SEPARATOR.

No. 857,248.

Specification of Letters Patent.

Patented June 18, 1907.

Application filed July 21, 1904. Serial No. 217,445.

To all whom it may concern:

Be it known that I, WILLY MEYER, of Hameln, Germany, have invented an Improved Seed-Separator, of which the following is a specification.

This invention has reference to an apparatus for separating the spherical grains of plants, sand and other impurities from wheat and other grain as well as for sorting the different kinds of wheat by employing an endless band which replaces the usual sieves.

In the annexed drawings, given by way of example, is shown a form of an apparatus constructed according to this invention.

Figure 1 is a longitudinal section of the apparatus. Fig. 2 is a cross section of same. Fig. 3 is a plan view of a portion of the sorting band and Fig. 4 a cross section of this band.

The apparatus comprises a reciprocating sieve frame *a* carrying inclined sieves *b*, beneath which a wide metallic endless band or belt *c* travels over rollers, and is provided with recesses *d*, in the form of pockets. This band travels slowly between the sides of the sieve frame in the opposite direction to the gravity movement of the grains to be separated. A jerky reciprocating motion is given to the sieve frame by any suitable known mechanism.

The feed hopper *e* for the grain to be treated is furnished with a feed roller *f* in a well known manner and delivers the grain upon the inclined sieve *b*. As the grain passes over the sieve, the smaller grains which it is desired to remove fall through the sieve holes upon the band *c* the sizes of the holes in the latter being chosen according to the grain to be sorted. The spherical grains or smaller grains are received according to their size and shape and are conducted to the rear, where they drop out at *x*, where the endless band travels around the driving drum. The larger sorted and cleaned grain drops out at *g*, at the lower end of the band.

To prevent the smaller grains separated from being carried to the front, a transverse scraper *h* is arranged near the upper end of the band. This scraper *h* allows the smaller grains which lie in the recesses *d* to pass while holding back the grains which are to pass to the outlet *g*. The metallic band is furnished with a brush *i* which assures the cleanliness of the sieve *b* by passing along the under side thereof.

The metallic band with recesses can be replaced as shown in Fig. 1 of the drawing, by strips of metal formed with recesses bored or punched, and fixed upon roller chains. The band can also be formed of a plate of steel or copper furnished with punched recesses and fixed upon a belt. These two forms of the band are only given as examples and same can be varied as required.

Having now fully described my invention what I claim and desire to secure by Letters Patent, is:

In an apparatus for separating grain, a metallic transporting endless band having recesses forming pockets, and mounted in an inclined sieve-frame having a jerky reciprocating movement, sieves arranged above said band, a scraper arranged transversely of said band and adapted to permit the passage of the smaller grains while preventing the passage of the larger grains, means for driving said band in a direction opposite to the gravity movement of the grain thereon, and a brush secured to said band and adapted to clean the under side of one of the sieves carried by said frame.

In testimony whereof I have hereunto set my hand in presence of two witnesses,

WILLY MEYER.

In witness of—
LEONORE RASCH,
H. HALL HALL.
